UNITED STATES PATENT OFFICE.

AUGUST GRÄNTZDÖRFFER, OF MAGDEBURG, GERMANY, ASSIGNOR OF ONE-HALF TO
ADOLPH LIST, OF MAGDEBURG, GERMANY.

PROCESS OF OBTAINING SUGAR FROM MOLASSES.

1,095,852.

Specification of Letters Patent.

Patented May 5, 1914.

No Drawing.

Application filed July 19, 1913. Serial No. 779,964.

To all whom it may concern:

Be it known that I, AUGUST GRÄNTZDÖRFFER, engineer, citizen of the Kingdom of Prussia, Empire of Germany, residing at 5 Magdeburg, Germany, have invented certain new and useful Improvements in the Process of Obtaining Sugar from Molasses, of which the following is a specification.

My invention relates to improvements in 10 the process of obtaining sugar from molasses.

In the process of making sugar the juice is concentrated and allowed to stand to permit crystallization, after which the crystals 15 are separated from the syrupy residue. The syrupy residue is again concentrated and the sugar contained therein separated, and this process is repeated until finally molasses is obtained which still contains sugar, but does 20 not crystallize any more.

The object of the improvements is to provide a process whereby a large amount of the sugar which is still contained in the molasses coming from the last crystallization 25 can be obtained, and in which the residues coming from the first crystallizations are boiled down in such a way, that a white sugar is obtained which is suitable for treatment in centrifugal machines. With this 30 object in view to the residues coming from the first crystallizations after the crystals have formed a mixture is added which consists of molasses coming from the last crystallization and a solution of sugar. Thereby

an amount of sugar is obtained from the 35 molasses which is in excess of what has been added thereto in the form of sugar solution, and the sugar which is crystallized from the residues of the first crystallizations is improved. For example, if the quotient 40 of the residues of the first crystallizations is 70—75, and that of the molasses of the last crystallization 58—60, and a sugar solution of 60 Brix with a yield (rendement) of 75% of the sugar is added, molasses of a 45 lower degree of purity (say 56 to 58) is obtained by the treatment in a centrifugal machine. Besides the amount is less than in the ordinary process, and it can be further reduced when using the same molasses over 50 again (say to $\frac{2}{3}$ or $\frac{1}{2}$). The output in sugar which is thus obtained is increased accordingly.

I claim herein as my invention:

The herein described process of obtaining 55 sugar from the residues of the first crystallizations of the concentrated juice, which consists in boiling the said residues, and adding thereto after the crystals have formed a mixture of a sugar solution and 60 molasses from the last crystallization.

In testimony whereof I have hereunto set my hand in presence of two subscribing witnesses.

AUGUST GRÄNTZDÖRFFER.

Witnesses:

ERNEST L. IVES,
LUCIE OEHLMANN.
